(57) **CLAIM**

The ornamental design for a diaphragm turkey call wallet, as shown and described.

DESCRIPTION

FIG. 1 is a perspective view of an embodiment of the invention;

FIG. 2 is a perspective view of the other side of the embodiment shown in FIG. 1;

FIG. 3 is a rear view of the diaphragm turkey call wallet shown in FIG. 1;

FIG. 4 is a left side view of the diaphragm turkey call wallet shown in FIG. 3;

FIG. 5 is a front view of the diaphragm turkey call wallet shown in FIG. 2;

FIG. 6 is a right side view of the diaphragm turkey call wallet shown in FIG. 1;

FIG. 7 is top view of the diaphragm turkey call wallet shown in FIG. 1;

FIG. 8 is a bottom view of the diaphragm turkey call wallet shown in FIG. 1;

FIG. 9 is an outside view of the diaphragm turkey call wallet shown in an unfolded position;

FIG. 10 is an inside view of the diaphragm turkey call wallet shown in FIG. 1 in an unfolded position, showing various pockets for receiving, for example, a diaphragm turkey calls, hunting license credit cards or the like;

FIG. 11 is a top view of the diaphragm turkey call wallet shown in FIG. 10 in an unfolded position;

FIG. 12 is a bottom view of the diaphragm turkey call wallet shown in FIG. 10 in an unfolded position;

FIG. 13 is a right side view of the diaphragm turkey call wallet shown in FIG. 10 in an unfolded position;

FIG. 14 is a left side view of the diaphragm turkey call wallet shown in FIG. 10 in an unfolded position;

FIG. 15 is a perspective view of another embodiment of the invention;

FIG. 16 is a perspective rear view of the embodiment shown in FIG. 15;

FIG. 17 is a front view of the embodiment shown in FIG. 15;

FIG. 18 is a right side view of the diaphragm turkey call wallet shown in FIG. 15;

FIG. 19 is a rear view of the diaphragm turkey call wallet shown in FIG. 15;

FIG. 20 is a left side view of the diaphragm turkey call wallet shown in FIG. 15;

FIG. 21 is a top view of the diaphragm turkey call wallet shown in FIG. 15;

FIG. 22 is a bottom view of the diaphragm turkey call wallet shown in FIG. 15;

FIG. 23 is a view of the outside of the diaphragm turkey call wallet shown in FIG. 15;

FIG. 24 is a view of the opposite side of the diaphragm turkey call wallet shown in FIG. 15, showing various pockets for receiving, for example, a diaphragm turkey calls, hunting license credit cards or the like;

FIG. 25 is a top view of the unfolded diaphragm turkey call wallet shown in FIG. 24;

FIG. 26 is a bottom view of the diaphragm turkey call wallet shown in FIG. 24;

FIG. 27 is a right side view of the diaphragm turkey call wallet shown in FIG. 24; and,

FIG. 28 is a left side view of the diaphragm turkey call wallet shown in FIG. 24.
